UNITED STATES PATENT OFFICE

105,764

DESIGN FOR A GRIDDLE CAKE AND WAFFLE DISPENSING BOOTH

Herbert T. Hunter, Baltimore, Md., assignor to Doughnut Corporation of America, New York,
N. Y., a corporation of New York

Application February 2, 1937, Serial No. 67,398

Term of patent 14 years

To all whom it may concern:

Be it known that I, Herbert T. Hunter, a citizen of the United States of America, residing at Baltimore, in Baltimore City County, and State of Maryland, have invented a new, original, and ornamental design for a Griddle Cake and Waffle Dispensing Booth, of which the following is a specification, reference being had to the accompanying drawings, forming part thereof.

In the drawings:

Fig. I is a perspective view of the front of a griddle cake and waffle dispensing booth, showing my new design; and

Fig. II is a perspective view of the rear of the booth.

I claim:

The ornamental design for a griddle cake and waffle dispensing booth, as shown.

HERBERT T. HUNTER.
